M. J. PINKLO

CONNECTION FOR BEDSTEADS AND THE LIKE

Filed Feb. 20, 1924

Michael J. Pinklo, INVENTOR:
BY Everett & Rook, ATTORNEYS.

UNITED STATES PATENT OFFICE.

MICHAEL J. PINKLO, OF WEST NEW YORK, NEW JERSEY, ASSIGNOR OF ONE-FOURTH TO BERNHARD PROCHNOW AND ONE-FOURTH TO BERNHARD PROCHNOW, JR., BOTH OF GUTTENBERG, NEW JERSEY.

CONNECTION FOR BEDSTEADS AND THE LIKE.

Application filed February 20, 1924. Serial No. 693,976.

To all whom it may concern:

Be it known that I, MICHAEL J. PINKLO, a citizen of the United States, and a resident of West New York, in the county of Hudson and State of New Jersey, have invented certain new and useful Improvements in Connections for Bedsteads and the like, of which the following is a specification.

This invention relates to that class of connections shown in my prior application Serial No. 655,563, filed August 4, 1923, and the objects of the present improvements are to secure such a connection in which the wedgingly movable member shall normally be in position for the end of the rail to be inserted for engagement with respect to the post; to thus avoid any necessity for lifting the movable member to permit insertion of the rail end, and leave both hands free for other purposes; to utilize for the movable member a dog or cam pivoted to normally swing into position to admit the rail-end and adapted to be turned by engagement of the rail-end into locking engagement therewith; to provide the lower end of the cam, which is first engaged by the rail-end to turn the cam, with means for causing less friction there than at the point where the rail-end engages the cam for locking purposes, and to obtain other advantages and results as may be brought out by the following description.

Referring to the accompanying drawing, in which the same numerals of reference designate corresponding and like parts,

Figure 1 is a vertical sectional view of a portion of a bed post and side rail, taken on line 1—1 of Fig. 2, a portion of the depending flange of the side rail being shown entire;

Figure 2 is a plan of the same with a certain lug in section;

Figure 3 is a transverse section on line 3—3 of Fig. 2;

Figure 4 is a vertical section taken centrally of the post, connection and end of the rail, showing a modified form of cam, and

Figure 5 is a transverse section of the same on line 5—5 of Fig. 4.

In the specific embodiment of the invention shown in Figures 1—3 inclusive, 1 indi-

cates one of the posts of either the head-board or foot-board of a metal bedstead, and 2 indicates one of the side rails. The post 1 is shown square and hollow and the rail 2 is shown of angle iron, although both or either of these parts might be of other common and well-known form. To the outside of the post 1 is suitably secured, as by spot welding at 3, 3, a bracket 4 which is in general channel-shaped with a connecting portion or back 5 lying against the post 1 and wings 6, 6 projecting therefrom. One of the wings is shown with a lateral projecting lug 7 to which may be bolted a bar 65 extending to a similar lug on the similar bracket of the opposite post of the head-board or foot-board, said bar not being shown as it is common and well-known construction.

Between the wings 6, 6 of the bracket 4 is pivoted a cam 8, as by means of a pin 9 extending through the wings 6, 6, and having outside one of them a head 10 and outside the other a cotter pin 11, or any other well-known means for preventing escape of the pin. The cam 8 is shown reduced at its opposite ends to form hub portions 12, 12 and its middle portion projects at the opposite side of the pin 11 from the post 1, as at 13, sufficiently to normally overbalance the cam 8 and throw its inner lower projecting portion 14 against the back 5 of the bracket. Above this lower projecting portion 14 is a curved portion 15 which wedgingly engages the rail end, when inserted, to jam it toward the post.

The side rail 2 is shown provided with an end piece 16, the stem 17 of which is shown made fast to the side rail as by means of rivets 18, 18 extending through one of the flanges of the angle iron side piece. The outer end of the end piece is provided with a right angular arm 19, said arm being of such a thickness that it will jam between the back 5 of the bracket and the curved portion 15 of the cam 8 as the latter turns on its pins 9, due to pressing the end post of the rail downward. By hooking the arm 19 over the cam 8 when it is in normal position, the extremity of the cam first engages the lower inner projection 14 of the cam to

turn the same so that its curved portion 15 engages said arm, and then downward pressure upon the side rail 2 or its end piece 16 causes the said curved portion to wedge tightly against the arm 19 by further turning of the cam 8, it being understood that said curved portion 15 is eccentric with respect to the pin 9, as is common in cams. The parts, when locked, assume substantially the position shown in Figure 1, and a firm, tight connection will be made; at the same time, disconnection is readily effected by lifting the end of the side rail 2 upward out of the seat between the cam and back 5 of the bracket.

The end piece 16 of the side rail 2 is preferably provided with a second lateral arm 20, opposite the arm 19, and forming therewith a T-head, so that the side rail 20 can be reversed or turned upside down, as is useful in adapting a bedstead with angle iron side rails to be used either with or without slats.

In Figures 4 and 5 I have shown a movable wedging member 21 mounted between the wings 22 of a bracket 23, which member 21, is made hollow so that it can be stamped from heavy sheet metal or similarly made. The closed top 24 is uppermost and the opposite parallel legs 25, 25 depend and receive through themselves the pin 26. Preferably washers 27, 27 are placed upon the pin at opposite sides of the pivoted member 21 to space it from the wings 22, 22. The outer end 28 of the member or cam 21 is heavy enough to normally hold it in position to receive the end piece 29, as already described in connection with Figures 1-3, the eccentrically curved inner edges 30 of the legs 25, 25 engaging said end piece to wedge it in place. The lower ends of the legs 25, 25 are also adapted to be engaged at their inner edges by the end piece to tilt the cam into engagement with the end piece, and in order to ensure less friction at this part of the cam than at its eccentrically curved edges 30 I prefer to employ a friction roller 31 at the lower part of the cam mounted upon a pin 32 extending from one leg to the other.

Other modifications in the construction of my invention may be made by those skilled in the art, and the connection can be employed for posts and rails of any kind to which it is applicable, whether forming part of a bedstead or not; therefore, I do not wish to be understood as limiting myself except as required by the following claims when construed in the light of the prior art.

Having thus described the invention, what I claim is,—

1. The combination with a post having a bracket and a transverse member on said bracket movable wedgingly toward the post,

of an end piece on a rail or the like having a lateral arm to extend between said post and member and be jammed by the latter toward the post upon downward movement, said member normally being held out of jamming position and adapted to be engaged by the lateral arm of the rail and moved into said position.

2. The combination of a bracket adapted to be applied to a post and providing spaced projecting wings, a cam pivoted between said wings at a distance from the post, and an end piece adapted to be applied to a rail or the like having a depending arm to enter between the bracket wings at the side of the cam next the post and upon downward movement turn said cam to jam said arm toward the post.

3. The combination with a post having a bracket, and a cam on said bracket facing said post, of an end piece on a rail or the like having a lateral arm to extend between said post and cam and be jammed by the latter toward the post upon downward movement, said cam normally being held out of jamming position and adapted to be engaged by the lateral arm of the rail and moved into said position.

4. The combination with a post having a bracket, and a cam on said bracket facing said post, of an end piece on a rail or the like having a lateral arm to extend between said post and cam and be jammed by the latter toward the post upon downward movement, said cam being weighted to normally swing away from said post and having an extension adapted to be engaged by the lateral arm of the rail to swing the cam into engaging position.

5. The combination with a post having a bracket, and a cam on said bracket having at its side facing said post an upper engaging portion and a lower contact portion, said cam being weighted to normally hold said upper engaging portion away from the post and said lower contact portion toward the post, of an end piece on a rail or the like having a lateral arm adapted to extend between said post and cam and engage the lower contact portion to throw the upper engaging portion against said arm.

6. The combination with a post having a bracket, and a cam on said bracket having at its side facing said post an upper engaging portion and a lower contact portion, said cam being weighted to normally hold said upper engaging portion away from the post and said lower contact portion toward the post, of an end piece on a rail or the like having a lateral arm adapted to extend between said post and cam and engage the lower contact portion to throw the upper engaging portion against said arm, and means for causing said lower con-

tact portion to engage said arm with less friction than the upper engaging portion.

7. The combination with a post having a bracket, and a cam on said bracket having at its side facing said post an upper engaging portion and a lower roller, said cam being weighted to normally hold said

upper engaging portion away from the post and said roller toward the post, of an end piece on a rail or the like having a lateral arm adapted to extend between said post and cam and engage the roller to throw the upper engaging portion against the arm. 10

MICHAEL J. PINKLO.
